HIS ATTORNEY

UNITED STATES PATENT OFFICE.

AMBROSE H. ROSENTHAL, OF BROOKLYN, NEW YORK.

DESIGN FOR A VEHICLE-TIRE.

• 54,683.

Specification for Design.

Patented Mar. 9, 1920.

Application filed September 24, 1919. Serial No. 326,087. Term of patent 14 years.

To all whom it may concern:

Be it known that I, AMBROSE H. ROSENTHAL, a citizen of the United States, residing in Brooklyn, county of Kings, State of New York, have invented a new, original, and ornamental Design for Vehicle-Tires, of which the following is a specification, reference being had to the accompanying drawing, forming a part thereof.

The figure is a plan view of a vehicle tire showing my new design.

I claim:—

The ornamental design for a vehicle tire, as shown.

AMBROSE H. ROSENTHAL.

Witnesses:

CLARICE FRANCK,
EDWIN LEVISOHN.
